CONTROL SYSTEM FOR THEATER LIGHT-
ING CIRCUITS

Albert Le Roy Upton, St. Louis, Mo.

Application January 16, 1933, Serial No. 651,868

14 Claims. (Cl. 175—312)

This invention relates to a system for controlling electric circuits for theater lighting whereby the brilliancy of the lighting may be controlled at will.

5 One of the objects of this invention is to provide a system of controls which will give proportional dimming in a plurality of circuits; that is to say, the lamps of one unit may be dimmed proportionately and simultaneously with the 10 lamps of another unit without having equal brilliancy in the different units.

Another object of this invention is to provide a system which will lend itself conveniently to remote control. With the pre-set and selection 15 provided by this system, the controls are of such simplicity that means may be readily designed, by those skilled in the art, whereby manually operable means may be assembled at a location remote from the system proper.

20 Another object of this invention is to provide for an individual lighting unit having dual controls whereby the brilliancy of such lighting unit may be controlled proportionately and simultaneously with either of two selected groups of 25 other lighting units.

Another object of this invention is to provide pre-set and selector controls. By these means each individual lighting unit may be pre-set to be controllable by any one of a number of master 30 controls simultaneously with other selected units and whereby the brilliancy of the lighting units may be controlled by any one of a number of control circuits.

Another object of this invention is to provide 35 means whereby a group of selected lighting units may be faded in or faded out simultaneously with the fading out or fading in of another group of lighting units.

Other and specific objects will be apparent 40 from the following detail description taken in connection with the accompanying drawings, in which—

Fig. 1 is a diagrammatical illustration of one lighting unit with a plurality of controls therefor.

45 Fig. 2 is a diagram of circuit control means for use in connection with the embodiment illustrated in Fig. 1.

Fig. 3 is an illustration of another embodiment of this invention showing an optional manner of securing a dual control for each lighting unit.

50 In the illustration, Fig. 1, only one lighting unit is illustrated, it being understood that a theater lighting system will, of course, include a large number of these units and it being understood

also that each of such lighting units may be similar to the one illustrated.

Lamps 1 are supplied with alternating current through wires 2 and 3. The wire 2 is connected through a bar 4 of a relay 5 with a wire 6 which comprises one side of the alternating current main. A reactance unit 7 includes alternating current windings 8 and 9. These windings are connected in series in a circuit between the wire 3 and the other side of the alternating current supply. Thus, the wire 3 is connected to one side of the winding 8, the other side being connected to a wire 10, which is connected also to one side of the winding 9. The other side of the winding 9 is connected by a wire 11 and through a bar 12 10 of the relay 5 to a wire 13, which, with the wire 6, constitutes the alternating current mains.

The path then of the alternating current which supplies the lamps of the lighting unit is as follows:

20 From the wire 6, one of the alternating current mains, through the conductor bar 4 of the relay 5, the wire 2, the lamps 1, the wire 3, the winding 8 of the reactance unit, the wire 10, the other winding 9 of the reactance, the wire 11, the 25 bar 12 of the relay 5, and to the other main 13.

The reactance unit 7 includes a direct current winding 14, the arrangement being such that by varying the voltage passing through the winding 14 the alternating current may be varied 30 from zero to maximum line voltage. The construction and arrangement of the reactance unit, as here illustrated and described, is well known and in common use. This invention includes, however, an improvement in such reactance unit which may or may not be in the unit itself. Means are provided, as will hereafter be described, whereby the winding 14 may be influenced by either of two circuits. In the embodiment illustrated in Fig. 3 this dual control is effected, as 35 will hereafter be described, by using two direct current windings in place of the single winding 14, as illustrated in Fig. 1. It will be seen, therefore, that in the embodiment shown in Fig. 1 the reactance unit 7 is of standard and well known 40 construction, the means for dual control being provided by circuit controls outside and apart from the reactance unit proper.

One side of the winding 14 is connected to a wire 15 which is a supply main common wire 50 with several sources of direct current. The other side of the winding 14 is connected to a wire 16, which may be connected, as will hereafter be explained in detail, to one of several controlled circuits. A variable resistance 17, illustrated in 55

the drawings as a potentiometer, is connected to the wire 16; the other side of the potentiometer opposite the wire 16 being connected to a wire 18. It will be seen, therefore, that the voltage 5 passing through the wire 14 may be controlled by the potentiometer 17 from zero to the maximum voltage supplied through the wire 18. Thus, the brilliancy of the lamps 1 may be controlled from zero to the maximum brilliancy permitted 10 by the voltage of the circuit fed through the wire 18, by manipulation of the potentiometer 17.

The potentiometer 17 also serves as a bridge of high ohmic resistance connecting the two branches of the circuit 15—16. Thus, if a switch 15 in the line is opened while the current is on excessive sparking will not occur due to the leak through this bridge.

A switch 19 is adapted to connect the wire 18 selectively to wires 20, 21 and 22. The connections from the wire 20 will be later described in detail, it being understood at this time that the wire 20 is adapted to be connected selectively by a pre-set system and master controls of any one of a number of control circuits.

25 The wire 21 is for independent control. The wire 22 may be described a color master, which may in practice be common with all the lighting units of the same color. The wires 21 and 22 have switches 23 and 24 by which they may be 30 selectively connected to any one of a number of brilliancy control circuits, such as 37, 38 and 39 (see Fig. 2).

The wire 20 is adapted to be connected automatically either to wire 21 or to wire 22, according 35 to the one carrying the higher potential. In the embodiment illustrated in the drawings this function is performed by a polarized relay 25. Obviously, it may be accomplished by other means, such as a differential relay, the construction and illustration of which is well understood 40 in the art.

I have thus described an important part of 45 this invention whereby the brilliancy of the lighting unit may be controlled by two separate circuits. One of the uses of this control may be illustrated as follows: The circuit 27 may be set at such a maximum voltage that the lighting units 1 may not be brought to more than fifty 50 per cent. brilliancy when under the control of that circuit. I may, nevertheless, without making a change in settings of that circuit, bring the lighting unit up to full brilliancy by means of circuit 28.

The circuit wires 27 and 28 may be each connected through relays 31, 32, 33 and 34, and through manually operable selector switches 35 and 36 selectively with a plurality of control circuit wires 37, 38 and 39.

It will be understood that while only four 60 relays (31, 32, 33 and 34) are shown, there will ordinarily be more than this number of relays, since there will be one relay for each master control, which will later be described. It will be also understood that there will be a number of 65 selector switches (35, 36) corresponding to the number of relays and to the number of master controls; two only being shown, for convenience.

Having described briefly one of the purposes 70 of the relays, it being to connect wires 27 and 28 with control circuits, I will now describe their arrangement, the circuits for actuating them and the master controls. The master controls include master switches 41 and 42, two only being shown in the drawings but as many as desired may be provided. These master switches are adapted to

operate the relays of as many lighting units as 5 need be simultaneously controlled. The switches 41 and 42 are adapted to be connected to a wire 43, which with a wire 44 comprises a source of current supply. The circuit 43—44, of course, will supply a substantially constant voltage. Each master switch includes a conductor bar 45 and a contact 46 which is adapted to make contact, when the switch is moved, with the wire 43. Each switch also includes contacts 47 adapted to make 10 contact respectively with wires 48, each leading to a particular lighting unit. Each of the switches 41 and 42 also include a contact 49, adapted to make contact with a wire 50, which is common to all the lighting units. At A I have 15 illustrated connections for the lighting unit illustrated in detail, and at B I have illustrated connections for another lighting unit not otherwise illustrated.

Each lighting unit has a plurality of manually 20 operable switches 51; these switches are mechanically connected double switches. They are adapted to connect the appropriate wires 48 with a common wire 52 and also to connect the appropriate wires 50 with its appropriate wire 53. The wire 25 52 is adapted to be connected by a manually operable switch 54 to a wire 55 supplying the winding for the alternating current relay 5. The relay 5 is connected by a return wire 56 to the supply circuit wire 44. The switch 54 is mechanically connected by a shaft 57 to the switch 19 and thus operates in unison with it. The switch 54 is adapted to connect the wire 55 to the wire 52, as previously explained, to a wire 58 which may be termed a color master, or to an independent main 35 wire 59. The wires 58 and 59, termed the color-master and independent, respectively, are not to be confused with the wires 21 and 22, which were referred to by the same name since the wires 58 and 59 are connected with auxiliary operating 40 circuits, whereas the wires 21 and 22 are connected with brilliancy control circuits.

It will now be understood that a circuit is provided for operating the relay 5 which connects the alternating current supply for the lamps in 45 the lighting unit; that circuit may now be described. When it is desired to control the lighting unit through the master switch, current will flow from the wire 43 through the contact 41 of the master switch, the bar 45, the contact 47, wire 48, 50 the appropriate bar of a switch 51, the wire 52, switch 54, the wire 55, the winding of the relay 5, and the wire 56 to the wire 44. When, however, it is desired to operate the lighting unit either through a color main or the independent main, 55 current will flow from the wire 43 through either the wires 58 or 59, the switch 54, thence through the path already described to the wire 44.

Current for operating the relays 31, 32, 33 and 34 is supplied through the wires 53; one wire 53 60 being connected to a winding of one of the relays and none other, the other side of the windings of the relays 31, 32, 33 and 34 is connected to a common wire 60, which connects with the supply circuit wire 44. The arrangement is such that the 65 winding of each relay is appropriate and may be connected to a master switch. Thus the relay 31 is operable only when the master switch 41 is thrown; relay 32 is operable only when master switch 42 is thrown; and the relays 33 and 34 are 70 operable respectively when their respective master switches, not shown in the drawings, are thrown.

The course of the circuit for operating the relays 31, etc., may now be traced. From the wire 75

43 through contact 46, bar 45, contact 49, wire 50, switch 51, wire 53, winding of the relay 31, and wire 60 to wire 44. It has been stated, and will now be understood, that the relays 31 etc., 5 are adapted to connect the circuit wires 37, 38 or 39 with the wires 27 and 28. A wire 61 connects the fixed terminal of the switch 35 with a terminal 62 on the relay 31, and a wire 63 connects the fixed terminal of the switch 36 with a terminal 62 on the relay 32. Similarly the fixed 10 terminals of other switches, light switches 35, 36, will be connected respectively to terminals 62 of the relays 33 and 34. A conductor bar 64 on each 15 of the relays is adapted to connect the terminal 62 with a terminal 65. Each of the terminals 65 is connected to one side of a resistance 66, specifically shown in the drawings as a potentiometer, by a wire 67. The other side of each potentiometer 20 66 is connected by a wire 68 to a terminal 69 of its appropriate relay. A conductor bar 70 on each of the relays is adapted to connect the terminal 69 with a terminal 71 which in turn is connected to a wire 72.

In the embodiment specifically shown the wires 25 72 of the alternate relays are connected in common and lead to a wire 27 or 28. Thus, the wires 72 connected to relays 31 and 33 are connected to the wire 27 and the wires 72 appropriate to relays 33 and 34 are connected to wire 28. I 30 will now trace the course of the circuit supplying control current to the lighting unit and in order to do this I may also describe the operation of the device. The system may first be set as follows: The potentiometer 67 will be set, in the 35 position shown in the drawings, in such a manner as to offer no resistance. The switches 35 and 36 will be set as indicated, the switch 35 connecting with the circuit wire 37 and the switch 36 connecting with the circuit wire 38. Switches 40 51 appropriate to master switches 41 and 42 will be thrown. The potentiometer 66 proximate to the switch 35 will be set as shown to afford the maximum of substantially fifty per cent. brilliancy and the potentiometer 66 proximate to the switch 36 will be set to afford approximately seventy-five, per cent. brilliancy. When the proper cue is received by the operator the master switch 41 is operated. Thereupon, as previously indicated and by the circuits as previously traced, 45 the relay 31 will operate. Thereupon the circuit is established as follows: From the wire 37 through the switch 35, wire 61, bar 64 of the relay 31, wire 67, potentiometer 66, wire 68, conductor bar 70, wire 72, wire 27, relay 25, wire 28, 50 potentiometer 17, wire 16, winding 14 of the reactor 7, wire 15, which with wire 37 constitutes the supply circuit. The alternating current circuit has been closed by operation of the relay 5 in a manner which has heretofore been described. 55 The brilliancy then of the lighting may be controlled by changing the voltage in the circuit 15-37. That is, it may be controlled up to fifty per cent. brilliancy as fixed by the potentiometer 60.

65 If, however, in the succeeding scene, it is desired to increase the brilliancy of the lighting unit beyond that fixed at first, switch 42 may be thrown and control current will pass from the wire 38 through the switch 36, in a similar path to that already described, to the wire 28, then when the potential increases beyond that supplied by the circuit 15-37 the relay 30 will operate to cut out the wire 27 and cut in the wire 28.

70 Fig. 2 illustrates means for supplying and regulating potential in circuits 37, 38 and 39.

which have a common main 15. These circuits are fed respectively by generators 80, 81 and 82. The voltage delivered by these generators is varied by varying the voltage in the respective field windings 83, 84 and 85. These field windings 5 are connected on one side to a common main 86 and on the other side to wires 87, 88 and 89, respectively. These wires are connected, respectively, to one side of potentiometers 90, 91 and 92, the other side of which are connected to 10 switches 93, 94 and 95, respectively. These switches are each adapted to connect with wires 96, 97 and 98.

The wire 96 is supplied with current by a generator 99 and the wire 98 by a generator 100. The 15 wire 97, with wire 86, constitutes mains having any convenient source of direct current supply. The circuit 86-97, of course, will carry a substantially constant voltage.

The generators 99 and 100 have field windings 20 101 and 102, respectively, each adapted to be supplied with current from the circuit 86-97.

The voltage in the winding 101 may be regulated by a potentiometer 103 and the voltage in the winding 102 may be regulated by a potentiometer 104.

It will thus be seen that the voltage supplied in the circuits 37, 38 and 39 may be regulated by varying the voltage in the field of the respective generators 81 and 82, this being accomplished by manipulation of the potentiometers 90, 91 and 92. It will also be obvious that one or more of the windings 83, 84 or 85 may be connected with either generator 99 or 100, each of which has means for varying the voltage of its output.

It will be obvious to those skilled in the art that the means provided for controlling voltage in the various circuits is extremely flexible and convenient to the many and varied situations 40 which arise in the control of theater lighting circuits.

Fig. 3 illustrates another embodiment by which the brilliancy of the lighting unit may be controlled by either of two control circuits. As in 45 the preceding embodiment lamps 1 are supplied with alternating current through wires 2 and 3. The reactance unit 7 includes alternate current windings 8 and 9 which are connected in series by wire 10 and connected in circuit between the wires 3 and 11, the wires 2 and 11 constituting the leads from a source of alternating current supply. The construction already described is the same as that which is included in the embodiment shown in Fig. 1. In the embodiment 50 shown in Fig. 3, however, the reactance unit 7 is provided with two direct current windings 110 and 111. One side of each of these windings is connected to the wire 15 which is a common main for the control circuits and the other side of the 55 windings 110 and 111 are connected, respectively, to the wires 27 and 28, which may be supplied with current as in the embodiment illustrated in Fig. 1.

It is contemplated that in actual practice 65 means will be provided whereby, when one of the relays 31, 32, 33 and 34 is operated, all other relays in a series will be locked out. In the arrangement shown in the drawings, when one odd numbered relay is operated all other odd numbered relays should be locked out, and when an even numbered relay is operated all other even numbered relays should be locked out. One means for doing this is illustrated in my Patent No. 1,878,304, issued September 20, 1932. In 70 75

addition to that method, the circuit for operating a particular relay may be connected through conductor bars on all other relays in the same group in such a manner that such other relays 5 will complete the circuit, when all of them are at rest, but will break the circuit when any one of the group is operated. In order to simplify the drawings this means is not illustrated. Some such means, however, should be provided in order 10 to prevent connecting the reactor winding with more than one control circuit by accident. Such an accident would cause one control circuit to affect the other control circuit, thus preventing the independent control of such two circuits.

15 In the embodiment specifically illustrated and described the master switches 41 and 42 are adapted to close circuits operating both the relay 5, for the alternating current supply, and the relays 31, 32, 33 and 34, for the control circuits. 20 Each of these master switches may be replaced with two master switches, one controlling the circuit for the alternating current supply relay and the other switch for controlling the control circuit relays. That is to say, one switch will be 25 adapted for connecting the wires 48 and the other switch will be adapted for connecting the wire 50. An advantage may be obtained by that method, in that the master switch connecting the wire 50 may be operated in advance of the alternating current supply relay 5, thus causing a 30 magnetic flux to build up in the reactor and rendering the system adaptable for immediate control when the alternating current circuit is closed. In the arrangement shown in the drawings and specifically described, even though the 35 system is set for full brilliancy there will be a considerable interval of time elapsing after the master switch is thrown before the lamps come to their full brilliancy. If, however, the master 40 switch is divided, as suggested, and the control circuit is closed slightly in advance, the lamps will come to their full brilliancy immediately upon closing the alternating current supply relay.

It will be obvious that parts of the invention 45 may be used without the whole, that additional controls may be provided, and that various changes may be made in the details of construction, within the scope of the appended claims, without departing from the spirit of this invention.

I claim:

1. In apparatus of the character described, a reactor, a plurality of direct current circuits, means for influencing said reactor by one only 55 of said circuits at a time automatically according to the circuit having the higher potential, and means for selectively varying the potential in said circuits.

2. In apparatus of the character described, a 60 reactor having a core adapted to be influenced by a unidirectional current, a plurality of direct current circuits, means for influencing said core by one only of said circuits at a time automatically according to the relative voltages of the circuits, and means for selectively varying the potential in 65 said circuits.

3. In apparatus of the character described, a reactor, a direct current winding on said reactor, a plurality of circuits, means effective automatically for placing said winding selectively in the one of said circuits carrying the higher potential, and means for selectively varying the potential in 70 said circuits.

4. In apparatus of the character described, a 75 reactor, a direct current winding on said re-

actor, a plurality of circuits, a switch for connecting the winding to one of said circuits selectively, a relay connected and adapted to operate said switch to connect the winding in the circuit having the higher potential, and means for selectively varying the potential in said circuits. 5

5. In apparatus of the character described having a plurality of lighting units, a control circuit for each of said units, a resistance variable at will in each of said circuits, a plurality of supply circuits, means for connecting each of said control circuits selectively to any one of a plurality of said supply circuits, generators adapted to supply respectively said supply circuits and each having an exciting winding, a circuit for each of said 15 windings, a resistance variable at will in each of said last named circuits, a plurality of generators, means for selectively connecting each of said last named circuits to any one of a plurality of said last named generators, and means for varying at 20 will the voltage of each of said last named generators.

6. In apparatus of the character described having a plurality of lighting units, a plurality of circuits pertinent to each unit only arranged and adapted to supply the voltage effective to control 25 the brilliancy of such unit, a relay in each of said circuits, a plurality of supply circuits, and a selector switch in each of said first named circuits adapted to connect said circuit with any one of a plurality of said supply circuits. 30

7. In apparatus of the character described having a plurality of lighting units, a plurality of circuits pertinent to each unit only arranged and adapted to supply the voltage effective to control 35 the brilliancy of such unit, a relay in each of said circuits, a plurality of supply circuits, a selector switch in each of said first named circuits adapted to connect said circuit with any one of said supply circuits, circuits respectively 40 for operating said relays, and unitary means for simultaneously closing a selected one of said last named circuits in each of a plurality of said lighting units.

8. In apparatus of the character described having a lighting unit, a supply circuit for said lighting unit, a relay in said supply circuit, a switch adapted to connect said relay selectively with any one of a plurality of operating circuits, a circuit adapted to control the brilliancy of said lighting 45 unit, a switch adapted to selectively connect said control circuit with any one of a plurality of supply circuits, and mechanical means connecting said two switches whereby they may be operated simultaneously. 50

9. In apparatus of the character described having a plurality of lighting units, a supply circuit for each of said units, a relay in each of said supply circuits, a plurality of operating circuits pertinent to each unit and each adapted to 60 operate the relay, means for selectively connecting the relay to any one of said operating circuits, a master switch adapted to close a plurality of selected operating circuits each pertinent to a separate lighting unit, a plurality of control circuits for controlling the brilliancy of a lighting unit, a relay in each circuit, a plurality of circuits each for operating a plurality of such last named relays, one in each of a plurality of units, pre-set switches in each of said last named circuits pertinent to the relays respectively, and a master switch for closing each of said last named circuits. 65

10. In apparatus of the class described having a lighting unit, a reactor for controlling the brilliancy of said unit, a direct current circuit in- 70

75

- cluding a winding on the reactor, a control circuit having pre-set switches adapted to connect it with a plurality of variable supply circuits common with other lighting circuits, and a master switch adapted to close said supply circuits, the improved combination including a color main circuit having means for varying its voltage at will, an independent main circuit carrying a substantially constant voltage, and a switch pertinent 5 only to said unit for selectively connecting said winding circuit with any one of said supply circuit, said color main circuit, or said independent main circuit.
11. In apparatus of the class described having 15 a lighting unit, a reactor for controlling the brilliancy of said unit, a direct current circuit including a winding on the reactor, a control circuit having pre-set switches adapted to connect it with a plurality of variable supply circuits common with other lighting circuits, and a master switch adapted to close said supply circuits, the improved combination including an independent main circuit carrying a substantially constant voltage, and a switch pertinent only to said unit 20 for selectively connecting said winding circuit with either said supply circuit or said independent main circuit.
12. In apparatus of the class described having 25 a lighting unit, a reactor for controlling the brilliancy of said unit, a direct current circuit including a winding on the reactor, a control circuit having pre-set switches adapted to connect it with a plurality of variable supply circuits common with other lighting circuits, and a master
- switch adapted to close said supply circuits, the improved combination including an independent main circuit carrying a substantially constant voltage, a switch pertinent only to said unit 5 for selectively connecting said winding circuit with either said supply circuit or said independent main circuit, and means in said winding circuit to vary its voltage at will.
13. In apparatus of the character described having a plurality of lighting units, a plurality of controlled circuits adapted to control the brilliancy of said units, generators adapted to supply respectively said circuits and each having an exciting winding, exciting circuits for said winding respectively, a variable resistance in each of said exciting circuits, a plurality of generators, means for varying at will the voltages of said last named generators, a supply circuit having a substantially constant voltage, and means for selectively connecting each of said exciting currents 10 with any of said generators or said constant voltage supply circuit.
14. In apparatus of the class described, the combination including a lighting unit, a reactor, a direct current winding on the reactor, a permanent circuit including the winding, a switch for selectively connecting said winding circuit with any one of a plurality of supply circuits, and a potentiometer in said winding circuit providing means for varying at will the voltage therein, 15 providing a high ohmic resistance between the branches of the circuit and positioned to close said winding circuit at all times.

ALBERT LE ROY UPTON.
